UNITED STATES PATENT OFFICE

123,437

DESIGN FOR A COOKSTOVE

Alvin G. Sherman, Grosse Pointe, Mich., assignor to Globe American Corporation, Kokomo, Ind., a corporation

Application March 30, 1940, Serial No. 91,369

Term of patent 14 years

To all whom it may concern:

Be it known that I, Alvin G. Sherman, a citizen of the United States, residing at No. 216 Lakeland Avenue, in the city of Grosse Pointe, county of Wayne, and State of Michigan, have invented a new, original, and ornamental Design for a Cookstove, of which the following is a specification, reference being had to the accompanying drawing, forming part thereof.

In the drawing the figure is a perspective view of a cookstove embodying my new design. The back and sides of the stove are substantially plain. The dominant features of my design reside in the portions shown in full lines.

I claim:

The ornamental design for a cookstove, substantially as shown and described.

ALVIN G. SHERMAN.
